PUMP

William N. Eddins, San Antonio, Tex.

Application September 8, 1939, Serial No. 293,871

8 Claims. (Cl. 103—52)

This invention relates to pumps and particularly to pumps of the type in which a gaseous pressure fluid is used within the well for producing the desired lifting force to remove fluid from the well.

This application is a continuation in part of my earlier application, Serial No. 191,616, filed February 21, 1938, for Fluid operated pump, which has matured into Patent 2,212,416, dated August 20, 1940.

The primary object of the invention is to provide a pump to be operated by means of a gaseous pressure fluid in a manner that a maximum of efficiency is obtained therefrom.

A further object of the invention is to provide a pump in which a valved piston movable within the pump barrel is so constructed that the valve therein will open by snap action when the end of the stroke is reached so that undesirable effects resulting from slow leakage or bleeding of the lifting fluid through the piston is avoided.

Still another object of the invention is to provide a pumping mechanism including a piston having a downwardly opening valve and provided with means for holding the valve normally closed, there being supplemental means for maintaining a seal between the piston and valve during the initial movement of the valve toward open position.

A more specific object is to provide a pump having a piston with a valve seat at its lower end, a sleeve being slidably positioned within the piston and having an auxiliary seat engageable with the valve and adapted to travel a limited distance therewith to maintain a seal during the initial movement of the valve toward open position.

Various objects and features of the invention will be understood from the following detailed description of a typical construction embodying the invention.

Throughout this description reference is made to the drawing in which:

Fig. 1 is a sectional view thru an illustrative embodiment of the invention, the piston within the structure being shown in elevation;

Fig. 2 is a vertical sectional view through the piston comprising an element of the invention;

Fig. 3 is a horizontal sectional view taken on the line 3—3 in Fig. 2.

The device of the invention controls the flow of pressure fluid from the lower end of the pump to furnish a lifting force upon the piston and to then release such fluid in a large integral quantity whereby the liquid to be lifted is removed

from the well in successive slugs or heads. To this end the illustrated embodiment comprises a pump tubing 1 which is lowered into a well and which terminates in a swaged nipple 2 threadably attached by means of a coupling 3 to barrel 4, the lower of which is in turn attached by means of coupling 5 to swaged nipple 6 supporting tubular member 7 provided with an upwardly opening standing valve 8.

10 Mounted within the upper swaged nipple 2 is a spider 10 having a plurality of axial openings 11 arranged about the axis thereof. Threadably secured in the center of this spider is a guide tube 12 which is closed at 13 at its upper end. 13 This guide tube 12 is secured in place by means of a lock nut 14.

The piston 15 which is best shown in Fig. 2 comprises a body portion 16 upon which are mounted seal rings 17 to engage the inner walls of the barrel 4 and prevent the slippage of fluids therebetween. Secured to the upper end of the body 16 and holding the upper rings 17 in place is a cap 18 which provides a chamber 19 having outlet openings 20 at the top of the assembly.

25 Eccentric openings 21 in the body 16 provide a passage between the chamber 19 and the lower portion of the piston which is formed by a tubular member 22 threadably secured to the body 16 at 23. It is apparent that by means of the construction just described there is a passage thru the piston, such passage including a lower chamber 25, eccentric openings 21, chamber 19 and the openings 20.

The lower end of the member 22 has a seating surface 26 to be engaged by a valve member 27 so that the passage thru the piston may be opened and closed. The valve 27 has an axial stem 28 extending upwardly therefrom having an enlarged portion 29 within a central bore 30 in the body 16. The enlargement 29 is provided with spaced peripheral grooves 31 and 32 which are engageable by balls 33 urged inwardly by means of springs 34 in a radial bore in the body 16. The lowermost groove 32 is located in such a plane on the enlargement 29 that the valve 27 is releasably held against the valve seat 26 when the balls 33 are held in place within the groove. In a similar manner the groove 31 is desirably positioned upon the enlargement 29 in such a plane that the valve will be in open position when this groove is engaged by the balls 33.

The enlarged portion 29 of the valve stem 28 extends upwardly and passes loosely through an opening 24 in the top of the cap 18. The enlargement 29 is threaded within the chamber 19

to receive lock nuts 40 and 41 of which the lowermost is provided with downward projections 42 which may engage the upper surface of the body 16 to prevent movement of the valve stem beyond a point at which the balls 33 engage the groove 31.

The upper end of the valve stem 28 has a cylindrical head 50 within the guide tube 12. A compression spring 51 abuts the upper surface of the head 50 and the upper end of the tube 12 while a similar spring 52 surrounds the valve stem below the head 50 and engages the nether surface of the head and the inwardly extending flange 53 at the lower end of the tube. This construction provides a resilient connection between the guide tube 12 and the valve stem 28 and serves a function that will more fully appear.

A compression spring 55 is also provided about the valve stem 28 between the lower end of the guide tube 12 and the upper surface of the piston 15. This spring exerts a force which constantly tends to move the piston 15 downwardly relative to the remainder of the pump assembly.

In the operation of the device as thus far described, fluid from the well enters the barrel 4 through the check valve 8 below the piston 15. Both liquid and gaseous fluids will thus enter the pump barrel and there will be an accumulation thereof until the pressure is sufficient to lift the piston 15 and component parts against the force exerted by the springs 51 and 55 and the weight of the column of superposed fluids.

The valve 27 will move together with the remainder of the piston assembly 15 until the force exerted by the spring 51 or the force effected upon complete compression of the spring is sufficient to retard further movement of the valve. The further movement of the piston will cause the balls 33 to move outwardly and as soon as the valve stem 28 is released from engagement by the balls 33 there will be a quick downward action of the valve stem under the influence of the compressed spring 51. In this manner the balls 33 will become engaged in the groove 31, thus releasably holding the valve in open position.

While it is not essential to the invention, it is preferable that the spring 51 be of insufficient strength to force the balls 33 from within the groove 32. Hence, initial relative movement of the piston and valve will take place when the spring 51 becomes completely compressed and serves as stop to prevent further upward movement of the valve 27 and its associated stem.

Attention is directed to the fact that during the initial movement of the valve 27 relative to the remainder of the assembly when the balls 33 are being displaced from within the groove 32, there is a slight opening between the valve seat 26 and the valve 27, whereby there is a leakage or bleeding of the liquid into and through the piston under the accumulated pressure therebeneath. Such action is desirable for the principal reason that a balancing of pressures may follow and result in the establishment of static conditions in the pump. In order to avoid such difficulty the bore within the member 22 is enlarged at 60 to receive a peripheral flange 61 upon a sleeve or supplemental sleeve or valve member 62 which is slidable within the member 22. The shoulder at the lower end of the counterbore 60 serves as a stop for the sleeve 62 and hence determines the limit of downward movement of the sleeve.

The lower end of the sleeve 62 is provided with

5 a seating surface 63 to engage the tapered surface on the valve member 27 and the sleeve is urged into engagement with this valve member by a compression spring 64 which abuts the upper end of the sleeve 62 and is held in place by means of a threaded ring 65 secured within the upper end of the member 22.

10 It is believed apparent that, as the valve member 27 begins downward movement and leaves the seat 26 as the balls 33 are being moved from within the groove 32, the sleeve 62 moves with the valve under the influence of spring 64 and hence maintains a seal. However, at the instant the balls 33 have moved from within the groove 15 32 the valve opens by snap action due to the upward movement of the piston and to a limited movement of the valve 27 downwardly under the influence of the spring 51. Downward movement of the sleeve 62 is terminated by the engagement of the flange 61 with the bottom of 20 the counterbore 60. Hence there is a quick opening of the passage through the piston assembly and slow leakage or bleeding of fluid through the piston is avoided.

25 It is to be understood that a unit such as that just described may be used singly or a plurality of units may be used at stages within a well bore, the number depending upon conditions to be satisfied in efficient and effective lifting of fluids within the well.

Broadly the invention comprehends a pressure actuated pump which is so constructed that a maximum of efficiency is obtained from the actuating fluid.

30 35 What is claimed is:

1. A fluid operated pump comprising a pump barrel, a piston therein, a standing valve at the lower end of the barrel, a fluid passage through said piston, a valve seat at the lower end of the piston, a valve in said passage, said valve including a stem extending longitudinally of the piston and having a loose connection with the barrel, means to resiliently oppose movement of said stem, and to also move the stem relative to the piston to open the valve, means normally urging the piston downwardly relative to said stem to maintain the valve closed upon said seat, and means for maintaining a seal with the valve to close said passage during initial travel 40 of the valve from position upon said seat.

2. A fluid operated pump comprising a pump barrel, a piston therein, a standing valve at the lower end of the barrel, a fluid passage through the piston, a valve seat at the lower end of the piston, a valve adapted to engage said valve seat, means for releasably holding the valve in open and closed positions, means for rapidly moving the valve to open position when released by said first mentioned means, and means for maintaining a seal between the valve and piston and closing said passage during releasing movement 55 of the valve.

3. A fluid operated pump comprising a pump barrel, a piston therein, a passage through said piston, a downwardly opening valve in said passage, means to hold said valve normally closed, said piston being movable upwardly by fluid pressure, a stem on said valve, a spring engaging said valve stem to oppose movement of the valve as the piston moves upwardly, and means movable with the valve during limited initial movement thereof from closed position for maintaining a seal preventing passage of fluid between the piston and valve.

4. A fluid operated pump comprising a piston,

a passage through said piston, a downwardly opening valve in said piston, means to hold said valve normally closed, and means for maintaining a seal closing said passage between the piston and valve during limited initial movement of the valve toward open position.

5. The combination of a valve having a valve stem extending outwardly therefrom, a tubular member surrounding said stem and having a seat engageable by said valve, a sleeve slidable within said member and having an auxiliary seat engageable by said valve, means resiliently urging said sleeve axially of the valve stem to maintain sealing engagement with the valve after the valve moves from the first mentioned seat, and means for limiting the movement of said sleeve, whereby the passage through the tubular member is maintained closed during initial movement of the valve to open position.

6. The combination of a tubular member having a seat on one end thereof, a valve adapted to engage said seat and close the passage through the member, means for releasably holding the valve in predetermined open and closed positions, and a supplemental valve seat movable relative

25 to said member to effect sealing engagement with the valve during initial and terminal movement of the valve as the valve moves respectively from and to closed position.

7. The combination of a tubular member having a seat on one end thereof, a valve adapted to engage said seat, means for releasably holding the valve in open and closed positions, a valve sleeve movable within said member, said sleeve having a seat adapted to engage said valve and form a seal therewith, and means to limit the movement of said sleeve after the valve moves from engagement with the first mentioned seat.

8. The combination of a tubular member having a seat on one end thereof, a valve adapted to engage said seat, means for releasably holding the valve in open and closed position, a valve sleeve movable within said member, a seat on said sleeve to engage said valve, resilient means 15 normally urging the sleeve toward the valve, and means for limiting the movement of said sleeve with the valve after the valve is unseated from the tubular member.
